(57) **CLAIM**

The ornamental design for a container for holding liquid for refilling an E-cigarette device, as shown and described.

DESCRIPTION

FIG. 1 is a perspective view of the container for holding liquid for refilling an E-cigarette device.

FIG. 2 is back side view of the container for holding liquid for refilling an E-cigarette device.

FIG. 3 is a front side view of the container for holding liquid for refilling an E-cigarette device.

FIG. 4 is a left side view of the container for holding liquid for refilling an E-cigarette device.

FIG. 5 is a right side view of the container for holding liquid for refilling an E-cigarette device.

FIG. 6 is a top view of the container for holding liquid for refilling an E-cigarette device; and,

FIG. 7 is a bottom view of the container for holding liquid for refilling an E-cigarette device.
